(57) **CLAIM**

The ornamental design for an environmental chamber light cap, as shown and described.

DESCRIPTION

FIG. 1 is a top perspective view of a environmental chamber light cap according to our new design;

FIG. 2 is an enlarged top perspective view thereof;

FIG. 3 is an enlarged bottom perspective view thereof;

FIG. 4 is an enlarged front view thereof, the rear view being the same;

FIG. 5 is an enlarged right side view thereof, the left side view being the same;

FIG. 6 is an enlarged top view thereof; and,

FIG. 7 is an enlarged bottom view thereof.

The dashed lines in FIG. 1 form no part of the claimed design and are included to show environment. The broken lines encircling the environmental chamber light cap in FIGS. 1 to 3, 6 and 7 indicate the bounds of the claimed design and form no part of the claimed design.
